(57) **CLAIM**

We claim the ornamental design for a dunnage cover, as
shown and described.

DESCRIPTION

FIG. 1 is a perspective view of the dunnage cover showing
our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines shown form no part of our design.
